UNITED STATES PATENT OFFICE.

JAMES H. RAND, OF NORTH TONAWANDA, NEW YORK.

INDEX-CARD AND METHOD OF TYPE-WRITING ON THE BOTTOM MARGIN THEREOF.

1,317,644.

Specification of Letters Patent. Patented Sept. 30, 1919.

Application filed November 11, 1918. Serial No. 262,075.

To all whom it may concern:

Be it known that I, JAMES H. RAND, citizen of the United States, and resident of North Tonawanda, in the county of Niagara and State of New York, have invented new and useful Improvements in Index-Cards and Methods of Type-Writing on the Bottom Margin Thereof, of which the following is a specification.

- 10 In card indexes of various kinds it is often desired to typewrite the title or other identifying description on the margin of each card instead of writing it by hand. No particular difficulty is encountered in doing this when the title is placed at the top of the card because typewriters generally are adapted to write at the extreme upper margin of a sheet or card. It is impossible, however, to typewrite at the extreme bottom margin of a card, because in the absence of special attachments or appliances, no provision exists in the ordinary typewriter to hold the extreme bottom margin in place on the platen to receive the writing.
- 15 20 25 30 35 40 45 50 55 60 65 70 75 80 85 90 95 100 105 110
- 20 In visible indexes, so-called, in which depending, overlapping cards are held in a frame with their lower margins exposed to display index titles or similar inscriptions, the title or indexing matter must appear at the extreme lower margin of the card, and it has been the practice either to write the title by hand, or, if the inscription is to be typewritten, it has been the practice to make the card longer vertically than its ultimate intended size in use, so that the inscription can be typewritten some distance from the lower edge of the sheet and while the sheet is properly held by the machine; after which all the lower part of the sheet, from a line immediately below the inscription, is removed either by cutting it off or by tearing it off on a previously prepared perforated or weakened line. This is wasteful of time and material, and also often results in a rough or ragged edge, or other imperfections in the finished index card.

The purpose of the present invention is to avoid these objections and to make it possible to produce an index card with a typewritten inscription on its extreme lower margin, without removing any part of the card or sheet, and without using special appliances on the typewriter to hold the extreme lower margin in place.

In the accompanying drawings which

illustrate my improved method and the card used in performing the method and resulting therefrom—

Figure 1 is a face view of the card; 60

Fig. 2 is a rear view of the card with the lower marginal portion folded rearwardly on the body of the card;

Fig. 3 is a section on line 3—3 of Fig. 1;

Fig. 4 is a section on line 4—4 of Fig. 2; 65 and

Fig. 5 is a sectional view illustrating the use of the invention in an ordinary typewriter.

The index card comprises a body portion 70 1, and a narrow marginal portion 2 at the bottom of the card. The card may be provided at its top with any desired form of hanger or support for mounting the card in a frame, such as the bar 3 connected to the 75 card with a hinge or otherwise. This forms no part of the present invention, however, and it is immaterial for the purposes of this invention whether such hanger is present or not, as the invention can be used in cards attached to hangers, or in cards for ordinary card indexes held in trays, or in insert-cards intended to be slipped into individual card holders.

The width of the marginal portion 2 corresponds substantially to the spacing between successive overlapped cards, and the consequent width of the exposed margins, when employed in indexes of the overlapping card, visible index type. 85 90

The narrow marginal portion 2 is divided from the body portion by a creased or weakened line 4 adapted to permit the marginal section 2 to be folded rearwardly flat upon the body portion. This weakened line is 95 preferably formed, especially if the card is of sufficient weight or thickness, by a cut or scored line passing part way through the card from its front face.

Now if the card is inserted in an ordinary 100 typewriting machine, it must be inserted margin first in order to write on the margin at all. When so inserted without folding, and typewritten upon the margin (which is now the upper margin), the writing will appear upside down when the card is removed and the card is placed in the index frame with the margin 2 at the bottom.

In order to perform the typewriting on the upper margin, and still have the writing 110 appear right side up on the face of the margin when the card is in use with its written

margin at the bottom, I fold the margin 2 rearwardly upon the body of the card, as shown in Figs. 2, 4 and 5, thus presenting the face of the folded margin 2 at the upper 5 margin of the back side of the card when the card is reversed top for bottom and back for front. With the parts in this position the card is inserted in the machine folded margin first, with the front face of the body 10 of the card against the platen P, and the back of the card outward in position to receive the impressions of the type. This brings the face of folded margin 2 at the top of the exposed side of the sheet in the 15 position of the upper margin of the back (now the exposed) side of the card (Fig. 5). The typewriting is now performed in the usual way on the face of the folded margin 2, the sheet being held in place by the 20 usual clips or fingers c.

The card is then taken out of the machine, and the typewriting will appear on the folded margin as shown in Fig. 2. Then the margin is unfolded and flattened out in 25 its original position, bringing the written surface again to the front face of the card, in which position the typewriting will appear right side up at the bottom margin of the card, as shown in Fig. 1.

30 I claim:

1. The method of typewriting an inscription on the extreme lower margin of the face of a card, comprising folding said margin rearwardly upon the body of the card, 35 thus presenting the face of the folded margin at the upper margin of the back of the card when the card is reversed top for bottom and back for front, typewriting on the face of the folded margin while it occupies the said position of upper margin of the back of the card, and unfolding the margin

again to bring its written surface to the lower margin of the face of the card.

2. An index card having a body portion, and a narrow marginal portion at the bottom of the card, the narrow marginal portion being divided from the body portion by a weakened line adapted to permit the marginal portion to be folded rearwardly flat upon the body portion to bring the front 45 50 face of the marginal portion into the position of a margin of the rear side of the body portion.

3. An index card having a body portion, and a narrow marginal portion at the bottom of the card, the narrow marginal portion being divided from the body portion by a weakened line adapted to permit the marginal portion to be folded rearwardly flat upon the body portion to bring the front 55 60 face of the marginal portion into the position of a margin of the rear side of the body portion, and a typewritten inscription appearing right side up on the face of the marginal portion when the card is unfolded and 65 positioned with the marginal portion downward.

4. An index card having a body portion and a narrow marginal portion at the bottom of the card, the card being cut part 70 through from the front face on a line dividing the narrow marginal portion from the body portion, to facilitate the folding of the marginal portion rearwardly flat upon the body portion, whereby the front face of 75 the marginal portion will be brought to the position of a margin of the rear side of the body portion.

Signed by me at North Tonawanda, N. Y., this 6th day of Nov., 1918.

JAMES H. RAND.
